UNITED STATES PATENT OFFICE.

ADALBERT VOLSWINKLER, OF SAN FRANCISCO, CALIFORNIA.

SPIRIT-LEVEL.

SPECIFICATION forming part of Letters Patent No. 600,756, dated March 15, 1898.

Application filed August 3, 1897. Serial No. 646,973. (No model.)

To all whom it may concern:

Be it known that I, ADALBERT VOLSWINKLER, of San Francisco, in the county of San Francisco and State of California, have invented certain new and useful Improvements in Spirit-Levels; and I do hereby declare the following to be a full, clear, and exact description of the invention, such as will enable others skilled in the art to which it appertains

10 to make and use the same.

This invention is an improvement in spirit-levels, the object of the same being to provide a device of this character which is not only serviceable in determining the level of 15 perpendicular and plane surfaces, but which will also accurately register the inclination of a surface, being therefore particularly useful in ascertaining the proper fall to be given to sewers, and also to give the proper inclination to brace-beams in building bridges, &c.

20 To the above ends and to such others as the invention may appertain the same consists in a spirit-level presenting a circular tube having liquid therein to form a bubble, the 25 said tube being applied to a beam having a straight edge, as hereinafter fully described, and specifically pointed out in the claims.

In the accompanying drawings, forming a 30 part of this specification, Figure 1 is an elevation of a spirit-level constructed in accordance with my invention. Fig. 2 is a sectional view. Fig. 3 is a detail view of the casting which is used to support the tube in place.

In carrying out my invention I apply the 35 same to a beam 1, having a straight edge, and in the side of this beam form a recess or circular groove to receive the essential parts of the invention.

2 Designates a circular semicylindrical casting, the edges of which are provided with outwardly-projecting flanges *a a'*, by which the covering-plates are secured thereto. The casting forms a channel in which is seated a circular glass tube 3, being properly seated 40 and held in place by plaster-of-paris or other cement. Secured to the outer flange of the casting is an annular plate 4, the inner edge of which extends into the channel to bear against the glass tube, while its outer end

45 50 projects so as to engage the beam 1 around the edges of the recess formed thereon. A disk or circular plate 5 is secured to the inner

flange of the casting, the edge of the same bearing against the inner side of the glass tube, and this disk or plate may contain 55 printed matter, as the stamp of the manufacturer or directions for setting the said devices into the beam 1 when said devices are sold separately. The circular tube is continuous, and before being sealed is filled with 60 a liquid sufficiently to present a bubble of the desired size. When the device is placed upon the beam, the annular plate is secured thereto by ordinary wood-screws. This annular plate is provided around its inner edge with marks 65 or degrees, as shown, the zero-mark being properly arranged with respect to the straight edge, being at a true right angle thereto.

From the foregoing it will be apparent that a spirit-level constructed in accordance with 70 my invention can be used for a number of purposes to which the ordinary spirit-level is not well adapted, the principal application of the invention being in connection with building sewers where the proper fall can be readily and quickly ascertained, as any inclination of the beam will cause the bubble to appear at the mark indicating the extent of the 75 inclination. It is also obvious that the device could be effectually used in building 80 bridges or other structures to give the proper inclination to the brace-beams.

It will be understood, of course, that instead of letting the devices into the side of a beam having a straight edge they could be 85 formed in a cylinder or casing to provide for applying the same to a straight edge or beam.

Having thus described the invention, what I claim as new, and desire to secure by Letters Patent, is—

1. In a spirit-level, the combination, with an annular glass tube, of an annular channeled metallic casing of corresponding radius to the tube, said casing being open at the top; an annular closure of a portion of the top of 95 the casing, overhanging the glass tube, the casing being suspended from the closure, and a straight edge on which said closure is suitably supported, said closure being suitably graduated or divided, substantially as de- 100 scribed.

2. In a spirit-level, the combination, with an annular glass tube, of an annular channeled metallic casing of corresponding radius

to the tube, said casing being open at the top, an annular closure of a portion of the top of the casing overhanging the outer portion of the glass tube, a circular closure overhang-
5 ing the inner portion thereof, one of said closures being suitably graduated or divided, one of said closures being secured to the straight edge, and the casing being suspended from the latter closure and supporting the
10 other closure, substantially as described.

3. In a spirit-level, the combination, with a straight edge having in one of its sides a recess, of an annular glass tube, an annular channeled metallic casing of corresponding
15 radius to the tube and containing said tube, said casing being open at the top, an annular closure of a portion of the top of the casing,

20 said closure being plane and supported on and substantially flush with the side of the straight edge around the recess, and the cas-
ing being secured to and suspended from said closure, and a circular closure overhanging the inner side of the glass tube, and sup-
25 ported on the casing, one of said closures be-
ing suitably graduated or marked, substan-
tially as described.

In testimony whereof I have signed this specification in the presence of two subscr-
ibing witnesses.

ADALBERT VOLSWINKLER.
